SELF STACKING CANS

Jack Novick, 619 Pauley Drive, West Hempstead, N.Y.

Filed Mar. 24, 1959, Ser. No. 801,579

1 Claim. (Cl. 220—97)

This invention relates to container constructions and more particularly to a container construction adapted to be stacked.

A principal object of the present invention is to provide a container construction shaped at its ends for stacking purposes.

Another object of the invention is to provide a can construction having a ribbed bottom and top, the bottom rib of the can being arranged to nest inside a ribbed top of a similarly constructed can construction.

A further object of the invention is to provide a truncated conical can construction having a ribbed top and a ribbed bottom with the ribs provided with interfitting split and projection respectively to serve as a keyway and key means so that the can construction may be stacked in only one position on another similar can construction.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is an elevational view of a number of containers in stacked relation, each container embodying the first form of my invention, in symbolical form.

Fig. 2 is a vertical sectional view taken on line 2—2 of Fig. 1.

Fig. 3 is a sectional view on an enlarged scale through a container construction embodying a modification of the invention, a portion of a similar container construction being shown stacked thereon.

Fig. 4 is a bottom plan view on a reduced scale of the container construction of Fig. 3, as seen from the line 4—4 of Fig. 3.

Fig. 5 is a top plan view on a reduced scale of the container construction of Fig. 3 as seen from the line 5—5 of Fig. 3.

Fig. 6 is a top plan view of a container construction embodying another modified form of the invention.

Fig. 7 is a bottom plan view of the container of Fig. 6.

Fig. 8 is a vertical sectional view of still another modified form of container construction shown in stacked relation.

Fig. 9 is a similar view of a still further modified form of container construction.

Fig. 10 is a view similar to Fig. 3 of yet another modified form of container construction.

Fig. 11 is a perspective view of the container shown in Fig. 1.

Referring in detail to the drawings, in Fig. 11 a container construction 10 made in accordance with the first form of the invention is shown. This is made of metal, cardboard, plastic or other suitable rigid material capable of retaining its shape when stacked as shown in Figs. 1 and 2. The container construction 10 has a cylindrical

2

hollow body 12 with a side wall 14 tapering downwardly and inwardly in conical formation thereby providing a body with a wider diameter at the top than at the bottom. The body has a flat bottom wall 16 and a flat top wall 18, these walls being shown in Figs. 1 and 2 formed integrally with the side wall but in practice the peripheral edges of such walls overlap the end edges of the side wall and are soldered or welded thereon as shown in Fig. 11.

10 Referring particularly to Fig. 2, the bottom wall 16 and the side wall 14 are joined by a rib 22, the rib extending slightly outwardly of the bottom wall and with the bottom wall defining a shallow recess 20 opening downwardly. The top wall 18 and the side wall 14 are joined by a rib 26, the rib extending slightly above the top wall and with the top wall defining a shallow recess 28 opening upwardly. A label 31 of any desired shape or size may be fastened to the outer surface of the side wall 14. This container construction may be readily mounted one upon another in stacked formation as shown in Figs. 1 and 2. The constructions and dimensions of the ribs and recesses are such that the recess 28 in the top wall 18 fittingly receives the annular rib 22 on the bottom wall of the container construction superimposed thereon in stacked relation, the rib on the top wall of the lower container construction interlocking with the rib on the bottom wall of the upper superimposed container construction as shown in Fig. 2. This interlock prevents the container constructions from tipping over.

30 The modified form of container construction 10' shown in Figs. 3, 4 and 5 differs from the form of Figs. 1 and 2 in that the top wall 18' is formed with an additional annular rib 27 which is spaced inwardly from the outer rib 26' constituting the juncture of the side wall 14 and top wall 18'. The rib 27 extending outwardly of the top wall a distance equal to the outer rib 26' so that the outer edges of the ribs are flush with each other. An annular groove 24 is formed in the top wall between the ribs 26' and 27.

40 The construction and dimensions of the annular ribs and annular groove are such that the annular groove 24 in the top wall 18' fittingly receives the annular rib 22 on the bottom wall of the container construction superimposed thereon in stacked relation, in interlocking relation with the ribs on the top wall of the lower container construction.

The form of container construction 10'' shown in Figs. 6 and 7 is the same as the form of Figs. 3 and 4 except that the annular rib 22'' on the bottom wall 16 is indented forming a protuberance 42 and the inner annular rib 27'' on top wall 18 is formed with a split or a notch 40. When a container construction 10'' is superimposed on another container construction 10'' in stacked relation, the protuberance 42 on the bottom wall fits into the notch or split 40 in the top wall of the lower container construction thereby interlocking the container constructions and guiding the container constructions to proper stacked position so that all of the labels 31 will be aligned.

60 Referring to the modified form of container 10^a shown in Fig. 8, in this form the body of the container has a straight side wall 24^a, a flat bottom wall 16^a and a flat top wall 18^a. The bottom wall 16^a is formed with an annular rib 22^a spaced inwardly from the side wall thereby forming an annular shoulder 36 at the bottom of the side wall. The rib 22^a extends slightly outwardly of the bottom wall. The juncture of the top wall and side wall is formed with an annular rib 26^a extending slightly outwardly of the top wall. The rib 26^a and top wall define a shallow recess 28^a.

The containers 10^a may be readily stacked one upon another as the annular rib 22^a on the bottom wall 16^a

is adapted to seat in the recess 28^a of the top wall of the bottom container, with the ribs interlocking and with the shoulder 36 engaging the rib 26^a on the top wall.

In the modified container 10^b shown in Fig. 9, the body of the container has a straight side wall 24^b with a flat bottom wall 16^b and a flat top wall 18^b. The juncture between the side wall 24^b and bottom wall 16^b is constituted by an annular rib 22^b extending slightly below the bottom wall. In this form, the juncture between the top wall 16^b and the side wall 24^b is formed by an annular rib 26^b slanting outwardly and upwardly of the top and side walls. The rib 26^b and top wall 18^b define a shallow recess 28^b. The containers 10^b may be readily stacked as the bottom rib 22^b is adapted to seat on the top wall in the recess 28^b at the base of the top rib 26^b of the lower container.

The form of container construction 10^x shown in Fig. 10 comprises a cylindrical hollow body having a straight side wall 24^x, a flat bottom wall 16^x and a flat top wall 18^x. The bottom wall 16^x is formed with an annular rib 22^x spaced inwardly from the peripheral edge thereof, the rib extending outwardly of the bottom wall a slight distance. The side wall 24^x is formed with an annular flange 40 depending downwardly therefrom and forming an extension thereof. The bottom edge of the flange 40 is flush with the bottom edge of the side wall 24^x. The top wall 18^x is also formed with an annular rib 26^x spaced inwardly from its peripheral edge a distance shorter than the distance spacing the rib 22^x of the bottom wall. The rib 26^x extends outwardly of the top wall a slight distance and with the top wall defines a shallow recess 28^x. An annular flange 42 is formed on the top edge of the side wall 24^x forming an extension thereof. The outer edge of the annular flange 42 is flush with the outer edge of the side wall 24^x. The containers 10^x may be readily stacked one upon another as the annular rib 22^x on the bottom wall is adapted to seat in the recess 28^x of the top wall of

the bottom container, with the ribs 22^x and 26^x interlocking with each other as shown in Fig. 10.

The several ribs, grooves, protuberances and notches can be formed by well known material working machinery at low cost.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

A stack of containers, each of said containers comprising a truncated conical body having a flat circular wider top wall and a narrower flat circular bottom wall, said top wall having a peripheral rib defining a recess with said top wall, said bottom wall having a continuous bottom peripheral rib, the bottom rib of each upper container fitting into the recess in the top of each lower container, the top wall of each container having another continuous rib disposed concentrically within the first-named rib and defining a groove therebetween, the bottom rib of each upper container fitting into the groove at the top of the lower container, the bottom rib of each container having a radially extending projection, said other rib at the top of each container having a notch, the projection at the bottom of each upper container fitting into the notch at the top of each lower container.
